His Attorney.

UNITED STATES PATENT OFFICE.

ELIJAH T. HARRIS, OF CHICAGO, ILLINOIS.

DESIGN FOR A BRACKET.

SPECIFICATION forming part of Design No. 15,788, dated February 10, 1885.

Application filed June 16, 1884. Term of patent 7 years.

To all whom it may concern:

Be it known that I, ELIJAH T. HARRIS, a citizen of the United States, residing at Chicago, in the county of Cook and State of Illinois, have invented and produced a new and original Design for Brackets, of which the following is a full, clear, concise, and exact description, reference being had to the accompanying drawings, forming a part of this specification.

My bracket or shelf is designed especially as an ornament for dressing-cases and other articles of toilet furniture. A bracket on each side of the mirror of a dressing-case produces a novel and very beautiful effect.

My design consists of a disk-shaped bracket-shelf with raised edge on a projecting arm having an approximately-circular outline, *e*, with elliptical ornamental openings *i*, extend-

ed portion *h*, and scalloped central ring, *f*, as shown in Figures 1 and 2. The disk *a* is provided with the raised edge *b*. The supporting-arm *c* may be of the form shown.

d is a portion of the wood-work of the toilet furniture.

25

I claim—
The disk-shaped bracket-shelf on a projecting arm having an approximately-circular outline, *e*, with elliptical ornamental openings *i*, extended portion *h*, and scalloped central ring, *f*, as shown.

In witness whereof I hereunto subscribe my name this 30th day of May, A. D. 1884.

ELIJAH T. HARRIS.
